US00D877606S

(12) **United States Design Patent**
Strothmann et al.

(10) **Patent No.:** **US D877,606 S**
(45) **Date of Patent:** **** Mar. 10, 2020**

(54) **RETAINING CLIP**

(71) Applicant: **Jennmar SanShell, LLC**, Pittsburgh, PA (US)

(72) Inventors: **Kris Strothmann**, Dix, IL (US); **Bobby Reese**, Fayetteville, WV (US)

(73) Assignee: **Jennmar Sanshell, LLC**, Pittsburgh, PA (US)

(**) Term: **15 Years**

(21) Appl. No.: **29/632,820**

(22) Filed: **Jan. 10, 2018**

(51) LOC (12) Cl. **08-08**

(52) U.S. Cl.

USPC **D8/395**

(57) **CLAIM**

The ornamental design for a retaining clip, as shown and described.

DESCRIPTION

FIG. 1 is a perspective view of a retaining clip showing our new design;

FIG. 2 is a right view thereof;

FIG. 3 is a left view thereof;

FIG. 4 is a rear view thereof;

FIG. 5 is a front view thereof;

FIG. 6 is a top view thereof;

FIG. 7 is a bottom view thereof; and,

FIG. 8 is a perspective view of the retaining clip shown in FIG. 1, showing the retaining clip secured to a drill bit. The broken lines shown in FIG. 8 are environmental only and not part of the claimed design.

1 Claim, 7 Drawing Sheets
